UNITED STATES PATENT OFFICE.

MARSHALL B. LLOYD, OF MENOMINEE, MICHIGAN, ASSIGNOR, BY MESNE ASSIGNMENTS, TO LEVI H. GREENWOOD AND GEORGE A. KEYWORTH, BOTH OF GARDNER, MASSACHUSETTS, AND WILLIAM E. HOLMAN, OF LEOMINSTER, MASSACHUSETTS, TRUSTEES.

REED ARTICLE AND METHOD OF PRODUCING IT.

Application filed April 2, 1920. Serial No. 370,729.

To all whom it may concern:

Be it known that I, MARSHALL B. LLOYD, a citizen of the United States, and a resident of Menominee, Michigan, have invented certain new and useful Improvements in Reed Articles and Methods of Producing Them, of which the following is a specification.

My invention relates generally to the production of reed articles and relates more particularly to the production of reed articles comprising a frame and a reed-fabric covering therefor.

Prior to the inventions disclosed in applicant's Patents Nos. 1243079, 1243080, 15 1243081, and 1243082, it was universal practise, in the manufacture of reed articles having a frame, to secure the stakes in the frame and to weave the filler strands over and under the stakes, 20 meantime conforming or shaping the fabric to the frame. Applicant provided a revolutionary method of producing articles of this kind, one inventive idea of which was the manufacture of reed fabric independent of the frame in a manner convenient for the 25 weaving operation and thereafter applying the fabric to the frame, and there securing it in a permanent manner.

The present invention, at least in some of 30 its aspects, relates generally to the production of reed articles under one or more of the methods outlined in the aforementioned patents, and the general object of the invention is to provide a method of improving 35 the manufacture of reed articles of certain kinds.

A further object of my invention is to provide a reed article, and the method of producing the same, in which the reed fabric should not only serve as a covering for 40 the frame, but should also serve as a cushion or spring back for the article.

Another object of the invention is to provide a method of producing reed articles 45 wherewith it shall be unnecessary to use braid, lining or other finishing materials, to finish parts which heretofore required the application of such finishing materials.

Another object of my invention is to provide a method of producing reed articles 50 wherewith it shall be possible to produce them more quickly; with less waste; by means of unskilled workmen; and by the

use of which the resulting article shall be one of substantial and pleasing character 55 or configuration.

My invention consists generally in a reed article, and in the steps, acts and sequence thereof for producing same, whereby the above named objects, together with others 60 that will appear hereinafter, are attainable. My invention will be more readily understood by reference to the accompanying drawings, wherein:

Fig. 1, is a side elevation of a somewhat 65 conical shaped endless reed fabric before the projecting stake portions thereof are turned or laid down.

Fig. 2, is a view of the fabric of Fig. 1, but showing the stakes laid down in customary 70 or desired manner to form an edging or selvage for the fabric.

Fig. 3, shows a step in the manufacture of 75 an arm chair using the fabric of Fig. 2, the view being a top plan view.

Fig. 4, is a perspective view of the reed 80 arm chair shown in Fig. 3, but showing it in completed form.

Fig. 5, is a side elevation of a tubular or 85 endless reed fabric, for use in producing other reed articles, before the stakes are laid down.

Fig. 6, is a perspective view of a reed 85 rocking chair in which the fabric of Fig. 5 has been used; and

Fig. 7 is a cross sectional view substantially along the line A—A of Fig. 6.

In the drawings, forming a part of this specification, I have depicted the manufacture of two reed articles both of which are 90 chairs but it should be understood that this is by way of illustration and not by way of limitation. The manufacture of reed chairs has been chosen as an illustration because it is a very good example of a class 95 of articles that can be advantageously manufactured by means of my invention.

The reed fabric shown in Fig. 1 may be produced in any desired manner but can be most conveniently produced upon a frame 100 or templet bearing the proper size relation to that part of the article frame with which it is to be used. The fabric, 1, as shown in Fig. 1, has projecting stake portions, 2 and 105 3, which are laid down, in the manner familiar to all reed weavers, for the purpose

of forming a finishing or selvage edge for the fabric. The laid down stakes in Figs. 2 and 3 are designated by the reference numerals 2' and 3'. The reed fabric shown in Fig. 2 is a tubular fabric of somewhat conical shape and is designated for use in producing a covering for the upper arm and back portions of an arm chair. Such a chair is shown in plan view in Fig. 3 wherein, 4, is the chair seat or bottom usually made of flat wood parts and upstanding from which are round frame members 5, 6, and 7. The members 5 and 6 are of such form that they constitute the arm and side portions of the frame, and the member 7, constitutes the back. The member 7, in this instance, is of somewhat U-shaped form having leg portions 7' that are secured in the seat 4. Between the leg portions 7', is a connecting member 8. Chair frames of this general construction, i. e. of round wooden framing, are much used in reed furniture manufacture, and it is for this reason that such a frame construction is shown. Obviously, if desired, the framing may be made of other materials or of different shapes.

The reed fabric of Fig. 2, is next placed around the arm chair frame members, as is well shown in Fig. 3, and it will be noted, 30 is of a size substantially twice the distance from one upright 5' of the chair, around the chair back, to the other upright 6'. It should also be noted that the chair flares upwardly and outwardly and for this reason the smaller end of the tubular fabric is placed adjacent the seat. The fabric is now secured to the members, 5, 6, 7' and 8, and along the edge portions of the seat frame 2. The outermost portion 9, of the endless 40 fabric (see Fig. 3) is now pushed inwardly so that it parallels the rear portion 10, of the fabric already secured to the outer side of the frame members, and so that the side portions 11 and 12, of the unsecured fabric 45 parallels the side portions 13 and 14, of the previously placed or secured fabric. The base of the fabric, when completely shaped, is positioned substantially as indicated by the dotted lines in Fig. 3. From this it becomes obvious that the endless, somewhat 50 elliptical shaped fabric originally formed, as thus secured and reshaped, is still of endless form but as applied to the upper portion of the arm chair is of substantial U-shape, an inner course of material substantially 55 parallelling an outer course, and spaced a distance apart just sufficient to enclose the small round frame members of the chair.

As is well shown in Fig. 4, not only does 60 the endless fabric 1, enclose the frame members, but it also serves in lieu of upholstery and at the same time furnishes back and side portions for the arm chair which are sufficiently yielding to furnish a comfortable chair, i. e. the fabric in a sense forms

a spring back. Since the fabric is endless in form there are no sharp projecting ends to mar the appearance of the article, on the one hand, or to catch and tear the clothing on the other. Furthermore, by this method 70 of procedure this very difficult weaving operation, as heretofore carried on, is reduced to very simple and easily followed steps which can be performed readily by unskilled workmen. Hence, it becomes possible to reduce the hitherto highly individualistic manual weaving of articles of this kind to a factory system, wherein the fabric can be produced in a manner convenient for the weaving operation and thereafter, quickly and easily, applied to the frame in a manner requiring very little by way of finishing and upholstering and still not only, not sacrificing the appearance and utility of the device, but actually enhancing, 80 85 both.

As before stated, my invention is applicable to a variety of articles and as illustrating another application thereof, I have depicted in Figs. 5, 6, and 7, steps followed in the production of a different type of chair. So far as the present invention is concerned it relates only to the production of the back of the chair from the seat upwardly.

The frame of the chair, which in the present instance is shown as a rocking chair, comprises the rockers 15 and 16, upstanding from which will be found members supporting the seat frame 17. Upstanding from the rear of the seat frame are the spaced risers, 18 and 19, see Fig. 7, which in turn are cross-connected as by members 20. Under the practise prevailing heretofore in the manufacture of such reed articles, the frame members 18 and 19 have been exposed to view, in some instances, thus marring the appearance of the chair and in the better grades, one side has been covered with reed and the other with upholstery material, which, while it is better and more comfortable than the unfinished back is considerably more expensive, and at the same time makes a complete closure for the back such as makes impossible the passage of air therethrough. This, in a measure, unfits the chair for one 110 of its primary uses which is that of a chair for summer use.

I have provided a means of completely finishing the chair back that will not, in a substantial degree, unfit the chair as an article for summer use, and which has many other advantages hereinbefore and hereinafter enumerated. In the production of the chair back a tubular fabric 21, is provided, as shown in Fig. 5. The projecting stake ends 22 and 23 are laid down in well known or desired manner, to finish the edge portions thereof and to prevent loosening of the filler strands. The length of the tubular fabric is equal to the height of chair back and its inner 130

circumference is equivalent to the distance around the spaced back frame members 8 and 9. As a next step, pressure is applied to the tubular fabric 21, to elongate it in such manner that it may be slipped over the frame members 18 and 19, as is well shown in Figs. 7 and 8. As thus placed, the bottom 24 is adjacent the seat frame of the chair and the space between the top portions 25 may be conveniently closed by the application of a strip of braid 26. The tubular fabric is secured to the members 18 and 19 as by means of brads or other suitable fastening devices.

In this manner the back chair frame members 18 and 19 are entirely enclosed so that no finishing or upholstering material is necessary along the frame members 18 and 19. The appearance of the chair is greatly improved, and, at the same time, because of the spaced relation of the inner portion 27 from the outer portion 28 of the tubular fabric a back is provided which yields comfortably when in use. This tubular or enclosing relation not only greatly improves the appearance of the article, but it also greatly simplifies the manufacture, thereof.

In qualifying the fabric or its elements as "reed" in the specification or claims, I mean to limit my invention to fabric the elements of which co-operate in the manner above described as characteristic of the stake and strand fabric made of reed, but to embrace such materials whether they be the natural reed, paper reed, or other material having the general characteristics of reed.

The above examples are sufficiently illustrative of the inventive idea and it is thought that the advantages thereof will be

apparent to those skilled in the art, without further comment, but, inasmuch as this disclosure will suggest to others modified methods and the embodiment in articles of different forms I do not wish to be limited to the specific articles nor to the precise method outlined except only as may be necessary by limitations in the hereunto appended claims.

I claim:

1. The method of producing reed articles having a frame and a reed fabric which consists in providing a frame that is substantially U-shaped, as viewed in one direction, in providing an endless reed fabric, and in placing the endless reed fabric around and conforming it to envelop the article frame in substantially U-shape.

2. The method of producing reed articles having a frame and a reed fabric which consists in providing a frame which is substantially U-shaped, as viewed from one direction, in providing an endless reed fabric, in placing the endless reed fabric around the outer part of the frame, the portion provided for covering the inner part extending away therefrom, securing the fabric to the outer part of the frame, and then forming the remaining fabric inwardly to cover the inner part of the frame.

3. A reed article having a frame which is U-shape, as viewed from one direction, and an independently woven reed fabric of endless form conforming to the U-shaped frame and enveloping both the inner and outer portions thereof.

In testimony whereof, I have hereunto set my hand, this 3rd day of February, 1920.

MARSHALL B. LLOYD.
